J. TAGGART.
MACHINE FOR EXCAVATING EARTH.

No. 11,242.

Patented July 4, 1854.

UNITED STATES PATENT OFFICE.

JOHN TAGGART, OF ROXBURY, MASSACHUSETTS, ASSIGNOR TO JOHN TAGGART AND RICHD. PITTS.

MACHINE FOR EXCAVATING EARTH.

Specification of Letters Patent No. 11,242, dated July 4, 1854.

To all whom it may concern:

Be it known that I, JOHN TAGGART, of Roxbury, in the county of Norfolk and State of Massachusetts, have invented an Improved Machine for Excavating Earth, and Which May Be Used to Advantage When Said Earth is Covered by Water; and I do hereby declare that the same is fully described and represented in the following specification and the accompanying drawings, letters, figures, and references thereof.

Of the said drawings, Figure 1, denotes a top view of my machine. Fig. 2, a side elevation of it. Fig. 3, a vertical, central, and longitudinal section of it.

In the said drawings, A, denotes the main platform upon which the operative parts of the machine are supported. Such platform being of a triangular shape and made to rest on two trailing wheels B, B', and a smaller guide wheel, C, fixed in the lower end of a vertical swiveling or turning shaft E.

F, is a secondary platform; it is made to rest on the primary platform, and to turn horizontally on a center post or short spindle, G, that is extended upward from the primary platform, and has a large tooth gear H, fixed firmly and immovably to its upper end and above the plane of the top of the secondary platform. The said secondary platform is made to sustain the crane, I, from which the excavating scoops are made to depend. These excavating scoops are formed of, or made like two cups a, b, respectively attached to the inferior arms of two levers, c, d, that are made to cross one another and turn on a common fulcrum or pin, e, extending through the prongs of a forked boom, K. The said forked boom, K, is made to extend through a rocket tube or eye L, that is jointed to a rocker frame, N, which turns on a bolt or pin at the head of the crane. The last mentioned rocker frame rotates in a plane transversely of the crane, while the rocker tube that is jointed to it is to be so joined as to be capable of moving or turning in a vertical plane that is perpendicular to the plane of movement of the rocker frame, N. The object of the rocker tube and frame is to permit the forked boom, K, to be swung or moved in any direction, either toward or away from the crane, or transversely of it. At the head or top of the crane there is a pulley or sheave, M, over which a rope,

N', extends from a windlass barrel, O. This rope after passing over the pulley at the head of the crane is separated into two branches or ropes, f, g, which extend downward, and in opposite directions through the boom (or around sheaves, h, i, arranged in the boom as seen in Fig. 4, which is a front view of the boom and excavating scoops), and are passed around sheaves, k, l (arranged respectively on the superior arms of the scoop levers) and are united in one rope and passed and made to work freely through the boom K, the boom being provided with a suitable orifice or passage for the rope to slide through. One end of this passage is shown in Fig. 4, while in Fig. 3, the passage is denoted by dotted lines. I would here remark that the said union of the two branch lines into one rope and carrying the same through the boom, and permitting them to slide freely through it is very important, for it enables the scoops to be operated differently from what they would be were the two branches, f, g, of the rope fastened at their ends directly to the boom. This will be seen by supposing, while such branches were so fastened to the boom, that during the act of closing the scoops together one of them should happen to bring up against some object which would arrest its movement; should this occur, no further movement of the other scoop toward its mate would take place, the whole operation of both scoops being stopped by the obstacle.

When the branches, f, g, are united together as described, or what is the same thing, when the main rope, N', is passed under and against one of the sheaves, h, i, and through the boom and thence around the sheave, k, thence backward through the boom, thence to and around the sheave, l, thence through the boom and against the other of the two sheaves, h, i, and finally has its end united to the rope at some point above the sheave, i, as seen in Fig. 2, the closing together of the scoops will not be arrested when one of them brings up against an obstacle such as will arrest its progress toward the other scoop, for as soon as the movement of a scoop is so arrested, the closing rope of the scoops, by its freedom to slide through the passages (in the boom) which is below the sheave passages, will be drawn through such passage, and the other scoop will continue to move toward its mate until it either meets it or is brought up

against the obstacle and so as to cause such obstacle or object to be firmly grasped by the two scoops. From this it will be seen, how perfectly such an application of the line to the levers of the scoops and to the boom facilitates the correct operation of the scoop. By applying the branch lines to work through the sheave passages in the boom and around the levers of the scoops, the power operating to close the scoops is caused to act to much better advantage, than were the branch ropes attached respectively to the scoop levers, and not made to work through the boom; for in this latter arrangement of them the greatest effect of the power, is when the scoops first move toward each other, the power diminishing as the scoops approach each other, whereas with my improved arrangement of the lines or ropes, the reverse is the case, the power of draft on the scoop levers increases as they approach the boom, or the scoops close together. This is as it should be, for the resistance to the scoops on entering the earth, increases as they pass into it. Consequently we desire the power to overcome such resistance to increase in proportion to the augmentation of the same. The said mode of applying the rope, N' , to the boom and the scoop levers, and providing the boom with what may be termed a "compensating passage" for the rope to slide through as described when one of the scoops brings up against any obstacle, and has its motion toward the other scoop arrested, constitute important improvements and render my excavating machine of great advantage not only in removing mud or common earth, but of seizing and lifting large masses of timber, rocks, or other ponderous bodies.

The application of the boom, K , and its working lines to the crane in such manner that the boom may not only have vertical movements, but lateral ones in any direction relatively to the platform on which the crane rests, or to a vertical line passing through the rocker tube L , gives to my improved excavating machine an important advantage when compared with many others, as it enables the boom when its scoops have grasped a stump or any timber that adheres firmly to the earth, to be moved laterally by the crane so as to bring a leverage on the scoops in a lateral direction by which the extraction of the stump or article from the earth may be greatly facilitated.

The scoops are formed very much like the halves of a bivalve shell, and each has attached to it one of two branch ropes m , n , which are connected to it (as seen in Fig. 2,) and to a rope, o , which extends upward and is carried around a sheave, p , (applied in the upper part of the crane) and thence descends to and is wound around a windlass

barrel, s , arranged as seen in Fig. 3. From this windlass barrel a rope, t , descends and has a weight, u , appended to it. On the shaft of the said windlass barrel is a brake wheel, u' , around which a spring brake, v , passes and is attached to and worked by a hand lever, w , arranged as seen in Figs. 1 and 2. One end of a rope, x , is attached to an arm or strut, y , extending from the top of the crane. From this strut a rope passes upward and through the top of the excavator boom, K , and around a sheave, y' , placed therein, thence it descends to the secondary platform as seen in the drawings. The object of this rope is to prevent the boom, K , from rising upward while the excavating scoops are being closed. This being done, either by draft on the lower end of the rope, or by winding the rope around a suitable belaying pin affixed to some proper part of the crane. The main driving shaft of the machine, z , is worked by a steam engine shown at, A' , or by a power applied to a crank, C' . On this shaft is a pinion gear, D' , that engages with a large spur gear, E' , that is fastened on a horizontal shaft, F' , (see Fig. 5, which denotes a transverse section of the machine taken through the axis of the shaft, F'). The said shaft, F' , carries the windlass barrel, O , which revolves freely upon and is so applied to it, as to be capable of being slid endwise upon it. To this shaft and windlass barrel, a common clutch, G' , is applied and the windlass barrel is moved on the shaft by means of a forked lever, H' , such movement being either for the purpose of clutching the windlass to the shaft, or unclutching it therefrom according to the direction in which the movement is made. When the windlass barrel is clutched to the shaft and said shaft is put in rotation, the rope of the windlass will be wound upon it, and by its action on the scoop levers will cause the excavating scoops to approach one another and finally close together. When they have closed together the line by which the boom is held downward is slackened. As soon as this takes place, the further movement of the windlass in winding up its rope will cause the boom and scoops to be elevated vertically. During the time the scoops are closing, the rope, o , will be wound around the windlass barrel, s , by the descent of the weight, u , the said weight serving to keep the rope, o , and its branch rope drawn taut.

As soon as the scoops have been elevated and moved over the spot where the contents of the scoops are to be discharged, an attendant lays hold of the brake lever of the brake wheel of the windlass s , and pressing it downward brings the brake into action upon the brake wheel, so as to arrest any rotary movement of it; this being done, he lays

hold of the fork lever of the windlass barrel, O , and moves it so as to unclutch the said windlass barrel, O , from the shaft on which it turns; as soon as this takes place, the boom and scoops are set free so that they can descend by the power of gravity, which taking place, their weight will be thrown upon the branch lines m , n , so as to cause the scoops to open apart and discharge their load; as soon as this takes place and the scoops have been moved over the ground to be excavated, the brake lever is to be elevated so as to remove the pressure of the brake from the brake wheel and permit the scoops to descend to the ground.

On the outer end of the shaft of the windlass barrel, O , a small beveled gear a^2 , is fixed. On a vertical shaft, b^2 , placed close to the beveled gear, a^2 , two other beveled gears, c^2 , d^2 , are fixed, one above the beveled gear, c^2 , and the other below it as seen in the drawings. This shaft, b^2 , slides freely in vertical directions, and is made capable of being raised or lowered by means of a lever, f^2 , and so as to bring either one of the gears, c^2 , d^2 , into engagement with the gear, a^2 , or both of them out of engagement with the same as circumstances may require. There is fixed on the lower end of the shaft, b^2 , a gear, e^2 , which is made to engage with a large stationary gear, H . The gear, e^2 , is to be made much wider than the gear, H , in order that the two gears may be in engagement with each other, whenever either of the gears, c^2 , d^2 , is in engagement with the gear, a^2 . The object of the beveled gear, a^2 , sliding shaft, b^2 , beveled gears c^2 , d^2 , and gears at the lower part of the shaft, b^2 , is for the purpose of enabling the crane to be turned around horizontally either in one direction or the other on the spindle, G , by the action of the driving power exerted through the shaft of the windlass, O , as will be readily understood by the description hereinbefore given.

My improved machine for excavating is intended to be operated, by a steam engine located on its secondary or crane platform; the boiler of such steam engine being seen at h^2 , in the drawings, i , being the chimney of said boiler. The mode of operation renders it very effective in excavating soil, and for the purpose of dredging rivers or harbors, &c. By means of its two scoops operating together in the manner above explained, the machine may be made to dig a vertical pit or hole and to operate to much better advantage in many respects, than the single scoop dredging machines which have their scoops drawn through the earth to be filled.

I do not claim the combination of a hand windlass with the line o , whereby such line would be wound upon the windlass by the power of a person applied to its spokes or levers; nor do I claim the combination of a

friction brake and brake wheel with a windlass, but—

What I do claim, is—

1. The combination of the gravitating weight, u , and its line, t , with the windlass barrel, s , and the brake wheel u' , so as to operate automatically and rotate both windlass and brake wheel, and not only take up the slack of the rope, o , while the scoops are being elevated as described, but at the same time to set the brake wheel ready for the action of the brake, when it becomes necessary to drop the scoops in order to discharge their load.

2. I do not claim the employment of a single line and two branch lines applied respectively to the two scoop levers and independently of their boom, but what I do claim is the arrangement of the branch lines, f , g , of the line N' , so as not only to operate through the ends of the scoop levers, but also through guiding or sheave passages of the boom, such an arrangement of the branch lines producing an increase of draft on the scoop levers during the operation of closing them as specified.

3. I also claim in combination with the afore described arrangement of the line, N' , through the sheave openings of the boom, K , and the two scoop levers or about their sheaves as specified, the union of the branches into one line in connection with the carrying such line through a compensating passage of the boom, K , and permitting it to slide freely through the same in manner as described, the same being for the purpose of enabling the scoops to close together or upon an object, whenever the movement of one of them, during the operation of closing them together, is arrested by contact with an obstacle as explained.

4. I am aware that a single scoop has been applied to a boom, and that boom made to slide through a slotted horizontal rocker shaft projected over the side of a scow. I am also aware that double scoops have been applied to a boom or an upright frame made to have vertical movements and to work through a derrick or platform. I do not therefore claim any such applications, of a boom of a single scoop, or the supporters of a set of scoops; neither do I claim the combination of a rocker tube or eye, L , with a rocker frame, N , as described and for the purpose of obtaining a compound movement, but what I do claim is the combining the boom, K , and the working ropes of it and its scoops with a crane, substantially as specified, so that scoops may be free to be moved not only vertically, but also in any direction either toward or away from, or laterally with respect to the crane and its platform whereby while the scoops are grasping a stump or other article adhering to the mud or earth, a lateral movement of the crane

may be employed to effect leverage on the
scoops in a lateral direction so as to aid in
disengaging the stump or article grasped by
the scoops and to effect this without in-
5 jurious strain on the boom or the parts
through which the boom slides.

In testimony whereof, I have hereto set

my signature, this twentieth day of October
A. D. 1853.

JOHN TAGGART.
